UNITED STATES PATENT OFFICE.

JOSEPH WARREN KESSEL, OF BROOKLYN, NEW YORK.

PEN-CLIP.

1,285,734.

Specification of Letters Patent. Patented Nov. 26, 1918.

Application filed August 6, 1918. Serial No. 248,572.

To all whom it may concern:

Be it known that I, JOSEPH W. KESSEL, a citizen of the United States, residing at Brooklyn, in the county of Kings and State of New York, have invented a new and useful Pen-Clip, of which the following is a specification.

The subject of this invention is a pen clip intended for use on a fountain pen, though adapted for other uses.

A main object of the invention is the provision of fastening means for the clip furnishing ventilation for the pen cap.

The invention also contemplates means for rigidly securing the clip to a pen cap.

A still further object of the invention is to generally improve the construction and enhance the utility of clips.

With the foregoing and other objects in view, which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

A practical embodiment of the invention is shown in the accompanying drawing, wherein:

Figure 1 is a view in front elevation of a clip constructed in accordance with the invention, and shown applied to a cap;

Fig. 2 is a longitudinal section taken on the line 2—2 of Fig. 1;

Fig. 3 is a longitudinal section taken on the line 3—3 of Fig. 2;

Fig. 4 is a cross section taken on the line 4—4 of Fig. 2.

Referring to the drawing by numerals of reference:

The usual fountain pen cap, to which the clip is shown applied is indicated by the numeral 10.

The clip is constructed of an elongated strip of resilient, or partially resilient metal 11, the free end of which is formed to provide, or has attached thereto a gripping

member such as the ball 12. At the other end of the strip 11 are formed, preferably integral with the strip, the laterally projecting tongues 13, which are adapted to enter slots 14 formed in the cap. The ends of the tongues are bent over, within the cap, to lock the clip firmly in place, as shown.

That end of the strip 11 at which the tongues 13 are situated is provided with an aperture 15, which is adapted to align with an aperture 16, formed in the cap 10, when the clip is in place on the cap, and an eyelet 17 is passed through these apertures and has its ends upset to securely rivet the clip to the cap. The opening through the eyelet provides sufficient ventilation for the cap, and reinforces the opening in the cap so that the same is not weakened by the provision of a ventilating hole or aperture.

Having thus described the invention, what is claimed as new and sought by Letters Patent, is:

1. A clip including in combination with a pen cap, a resilient strip disposed longitudinally of the outer face of the cap, the said strip and cap provided with alining apertures, and means inserted in the apertures for binding the strip to the cap and providing an aperture communicating with the interior of the cap.

2. A clip including in combination with a pen cap, a resilient strip disposed longitudinally of the outer face of the cap, tongues on the strip and passed through the wall of the cap, the inner ends of the tongues bent to clamp the strip to the cap, the said strip and cap provided with alining apertures, and means inserted in the apertures for binding the strip to the cap and providing an aperture communicating with the interior of the cap.

In testimony that I claim the foregoing as my own, I have hereto affixed my signature in the presence of two witnesses.

JOSEPH WARREN KESSEL.
